W. H. ORTMAN

CLOTHESLINE SUPPORT

Filed July 1, 1921

Patented Jan. 8, 1924.

1,480,006

UNITED STATES PATENT OFFICE.

WILLIAM H. ORTMAN, OF MILWAUKEE, WISCONSIN.

CLOTHESLINE SUPPORT.

Application filed July 1, 1921. Serial No. 481,822.

To all whom it may concern:

Be it known that I, WILLIAM H. ORTMAN, a citizen of the United States, and resident of Milwaukee, in the county of Milwaukee 5 and State of Wisconsin, have invented certain new and useful Improvements in Clothesline Supports; and I do hereby declare that the following is a full, clear, and exact description thereof.

10 My invention relates to improvements in supports for clothes lines and similar ropes or cables, and relates more particularly to that class of supports described in Patent Number 1,327,059 granted to me in the 15 United States on the 6th day of January 1920.

The object of my invention is to provide means whereby a clothes line may be quickly and securely strung from a plurality of 20 posts and connected to anyone of the latter depending upon the amount of rope required and the number of objects carried thereby.

Further objects of my invention are to 25 provide a device of the character described which may be cheaply and easily produced from a single piece of material; which is capable of effecting the desired securement of the clothes line, expeditiously; which includes means to prevent fraying and breakage of the line due to chafing against the metal of which the device is formed, and which is thoroughly reliable and efficient in use.

30 With the foregoing and other objects in view my invention consists in the novel features of construction, combination and arrangement of parts as will be hereinafter more fully described, illustrated in the accompanying drawings, and particularly defined in the appended claims.

In the drawings, wherein like characters of reference denote corresponding parts in the different views:—

45 Figure 1 is a perspective of a preferred form of my improved support, showing in dotted lines the manner of effecting securement of the end of a line therewith.

Figure 2, a partial longitudinal section 50 through the device on the line 2—2 of Figure 1, and

Figure 3, a plan view of a slightly modified form of the support.

55 Figure 4 is a modified form of the device showing the same provided with two lateral extensions.

Referring now to the drawings in detail, it will be observed that both forms of my invention are produced from a single piece of sheet material, with particular reference to the form illustrated in Figures 1 and 2, it will be noted that it includes a flat body portion 10 having extending from one end thereof, an elongated shank 11, which is approximately one-half the width of the 60 body portion 10 and which is doubled upon itself so that its free end overlies the adjacent flat face of the body portion. The free end of said portion is in turn bent to provide a hook 12 the open portion of which faces in the direction of the outer end of the shank hereinbefore mentioned.

In order to secure the two thicknesses or plies of metal together which constitute the shank 11, so that said shank will at all times 70 be maintained rigid, a U-shaped incision is cut in one of the plies and the tongue 13 formed thereby is passed through a slot, formed in the other ply after which it is bent over against the outer face of said second ply, thus forming a simple and efficient manner of accomplishing the purpose.

A part 14 of the body portion 10 projects laterally with respect to the shank 11, the same being connected with the body portion proper by a relatively narrow neck 15 formed by cutting depressions 16 in the respective ends of the body portion. These depressions are essential to the device I have produced, and, as shown, the edges of the 80 metal forming their inner rounded ends is swaged over to produce beads 17 which taper outwardly from the inner ends of the depressions and merge into the edges of the metal forming the sides thereof.

In connection with the hook 12 it will be noted that the bight portion thereof is disposed inwardly with respect to the outer depression 16, and that it is slightly curved transversely at its bight portion in order to more readily accommodate that portion of the line which is adapted to be engaged therewith.

As shown in Figure 1 the shank 11 is provided with an opening 18 adjacent its end, the same being adapted to receive therein the bight portion of a supporting hook or member 19, the latter being securely fastened to suitable posts or the like.

In the operation of my improved device, 105 assuming that a plurality of posts have each attached thereto one of my improved sup-

ports, and it is desired to stretch a line between two or more of the said posts. The free ends of the line are attached to a pair of the supports and each end being secured thereto in a manner similar to that illustrated in Figure 1, and if desired, any intermediate portion of the same may be supported by similar devices. In the latter instance, the line merely engages the hook 12.

10. If desired a second lateral extension, in all respects duplicate of the extension hereinbefore described may be provided on the body portion, and if this second extension is used as illustrated in dotted lines in

15. Figure 1 of the drawings, securement of the line with either or both extensions may be effected in a manner which is obvious.

10. In Figure 3 of the drawings is illustrated a device having the same relative arrangement of depressions 15' with hook 12' as in the form of the device first described but differing slightly from said first form in that the shank 11' is not doubled back upon itself and in that the hook 12' is formed by bending over a part of the body portion 10'.

From the foregoing, it is thought that the construction, operation and many advantages of the herein described invention will be apparent to those skilled in the art, without further description, and it will be understood that various changes in the size, shape, proportion and minor details of construc-

tion may be resorted to without departing from the spirit or sacrificing any of the advantages of the invention.

Having thus fully described my invention, what I claim as new, and desire to secure by Letters Patent is:—

1. A device of the class described formed of a single piece of material and cut to provide a shank, an extension arranged at one end of said shank, and having its opposite end portions bifurcated, a hook carried by the shank and formed adjacent said extension, and said furcations and hook adapted to receive therein the end of a clothes line.

2. A device of the class described formed of a single piece of material and cut to provide a shank, an extension carried by one end of said shank, furcations formed between said shank and extension, said shank being folded back upon itself and provided at its free end with a hook, an opening in said folded portion of the shank, a tongue cut from the under portion and passing through said opening for locking the two portions together, and said hook and furcations adapted to receive therein the end of a clothes line.

In testimony that I claim the foregoing I have hereunto set my hand at Milwaukee, in the county of Milwaukee and State of Wisconsin.

WILLIAM H. ORTMAN.
